US00D961594S

(12) **United States Design Patent** (10) **Patent No.:** **US D961,594 S**
(45) **Date of Patent:** **** Aug. 23, 2022**

(54) **BATTERY FOR AN ELECTRONIC DEVICE**

(71) Applicant: **Apple Inc.**, Cupertino, CA (US)

(72) Inventors: **Matthew David Hill**, Santa Clara, CA (US); **Dale T. Morgan**, San Jose, CA (US); **James B. Smith**, San Carlos, CA (US); **Ian Spraggs**, San Francisco, CA (US)

(73) Assignee: **Apple Inc.**, Cupertino, CA (US)

(**) Term: **15 Years**

(21) Appl. No.: **29/648,095**

(22) Filed: **May 18, 2018**

Related U.S. Application Data

(63) Continuation of application No. 29/613,506, filed on Aug. 10, 2017, now Pat. No. Des. 831,025.

CLAIM

The ornamental design for a battery for an electronic device, as shown and described.

DESCRIPTION

FIG. 1 is a bottom front perspective view of a first embodiment of a battery for an electronic device showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom front perspective view of a second embodiment of a battery for an electronic device showing the claimed design;

FIG. 10 is a top rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the figures show portions of a battery for an electronic device that form no part of the claimed design.
